RELAY

Fritz Schulte, Philadelphia, Pa., assignor to
Thomas D. Bowes, Bala-Cynwyd, Pa.

Application July 17, 1952, Serial No. 299,435

20 Claims. (Cl. 200—97)

1

This invention relates to relays, and particularly to relays with substantial immunity to vibrations and accelerative forces.

While the invention has particular relevance to a companion application now in course of preparation relating to an invention directed to circuits incorporating some of the features of Bowes Patents No. 2,465,006, of March 22, 1949, and No. 2,563,577, of August 7, 1951, in the utilization thereof in establishing progressive changes in output torque in the drive of automotive devices such as in automobiles, boats, and the like, the invention herein is of broader scope and incorporates improvements in relays per se which are of utility in any circuit use in which vibrations or accelerative forces are comprehended as being actually or potentially incident on a relay.

It is among the objects of the invention to improve the construction of relays; to provide a relay with damping so as to render it immune to reaction from extraneous forces other than electrical; to provide a relay spring-biased toward one setting and electrically biasable toward another setting against the spring bias; to provide a relay for controlling alternate circuits with a restricted relay motion; to provide a relay comprising a pivoted oscillatable member with damping means effective on the pivot to preclude motion thereof other than that which is predeterminedly desired; to provide a relay having damping imparting slow response to electrical energization or deenergization and which is inertially damped against accelerative forces; to provide a relay immune to accelerative forces including angular accelerative forces; to provide stops for relays which prevent bouncing to insure maintenance of the circuit condition existing at the time of contact with the stops; and to provide other objects and improvements as will appear as the description proceeds.

The relays of the type under discussion are those which are potentially exposed to accelerative forces of two forms. The first is a linear force acting at right, acute or obtuse angles of incidence to and lying in a plane containing the axis of rotation of the movable portions of the relay. These are absorbed without reaction by insuring that the axis of oscillation of the movable portions of the relay is exactly centered in the center of mass of the moving relay portions. The second are what may be designated as torsional accelerations in which the forces are nonlinear resultants of complex forces effecting angular incidence on the pivotal axis. In the instant invention these latter forces are absorbed

2

without reaction by providing a jack shaft with a second mass of equal inertia to that of the primary relay moving mass. The important feature of the connection between the main and jack shafts is that they are caused to have opposite directions of rotation. It will be obvious that within this broad concept the connections may be any suitable means that may be found most expedient. For instance, one of the simplest is to constitute the relay mass and the inertial mass as complementary segmental gears, in which case the two masses could lie generally in the same plane. Other forms of connections included spur gears, a pair of levers or arms mounted respectively on the respective shafts, with a pin and slot connection between the free ends of the arms, pulleys and a reversed belt may be used.

In securing the same inertia between the two masses, i. e. the inertia of the mass of the movable relay centered on the axis of the main shaft, and the inertia of a neutralizing mass, centered on the axis of the jack shaft, it will be understood that in the simplest form, with each mass shaped as a segmental gear in mutually complementary relation, the masses can be made identical with a 1:1 ratio between the rotation masses. This same principle of course maintains with the other forms of masses and interconnections when a 1:1 ratio is observed. If the masses on each shaft are of the same shape, diameter, and weight, and rotate oppositely in this same 1:1 ratio, they obviously will have the same inertia. Spur gears of the same diameter and number of teeth connecting the masses through their respective shafts or other 1:1 drive connections represent a perfect solution to the accelerative problems, as it makes no difference in this case how ponderous the masses, how slow or how fast the acceleration, or if the acceleration is rapidly changing direction or reverses, as in reciprocation.

In departures from the ideal situation described above it is pointed out that the ideal ratio of 1:1, may be changed to anything else desired, when complementary changes are made in the respective masses. For instance, if a gear with 100 teeth is mounted on the main shaft mounting the movable mass of the relay, in mesh with a pinion gear with 10 teeth on the jack shaft, the ratio becomes 10:1. Consequently to neutralize or counterbalance the given mass of the relay on the main shaft, it is only necessary to provide a mass on the jack shaft having one tenth of the inertia of the main mass. While

it is possible that this arrangement may not be quite as effective in all accelerative problems as the recited 1:1 mass ratio, as it is conceivable that a long drawn out circular acceleration might react more strongly on the large mass than on the smaller mass finally resulting in motion of both, there may be compensations attaching to the enhanced damping possible. Thus, if eddy current braking is used on the jack shaft mass, it is relatively ineffective at very low speeds of rotation of the latter. However, when its relative speed is as a factor of 10 to the main mass, this rapid rotation gives greatly enhanced braking. In any case however, as will be pointed out, the spring bias is applied to the main shaft, which may be weak in the 1:1 ratio of masses and rotational speeds, and may be much stronger in the higher ratios as recited, tending to minimize the reactions from such long continued circular accelerations.

In connection with the brake effects of the organization it is pointed out that this can be regulated or adjusted by increasing or decreasing the magnetism. However, if the magnetism is increased too much, the relay may be slow to react under certain conditions of use. If the magnetism is decreased in order to gain speed, there may be a bounce effect at the end of the relay stroke, which may actuate the circuit controllers more than once in a form of chatter. It is desirable to so absorb such impact as to stop the stroke without storing of energy such as to cause a bounce at such stop.

In carrying out the invention in an illustrative embodiment a first mass is mounted on a first shaft with the center of mass coincident with the axis of the shaft, a second mass is mounted on a second shaft with its center of mass coincident with the axis of the second shaft, a driving connection is established between the masses of predetermined ratio of rotation of the masses in opposite directions, the magnitude of said masses being predeterminedly such with reference to the ratio of relative rotations that the masses have the same inertia, a circuit controller is provided for actuation by said first mass as a function of angular motion thereof, electromagnetic means is provided for exerting torque on said first mass, and a spring bias effective on said first mass in opposition to such torque.

In the accompanying drawings, forming part of this description:

Fig. 1 represents a plan of an illustrative embodiment of the invention;

Fig. 2 represents a side elevation thereof;

Fig. 3 represents a bottom or reflected plan thereof;

Fig. 4 represents a fragmentary horizontal section thereof;

Fig. 5 represents a fragmentary vertical section therethrough;

Fig. 6 represents a fragmentary side elevation thereof;

Fig. 7 represents a fragmentary side elevation thereof;

Figs. 8, 9, 10, and 11 represent various views of further modifications of the invention.

Referring to Figs. 1 to 7, a support 10 is provided, such as a mounting plate, on which and on such auxiliary support means as may be necessary, indicated at 11, a main shaft 12 is journaled with its axis of oscillation generally normal to the spaced support elements 10 and 11. The upper end of the shaft 12 mounts a horizontal arm 13, normal to the axis of shaft 12,

journalling a roller 14 at its free end. The roller 14 in restricted motions of shaft 12 bears alternately against microswitch actuating levers 15 and 16. Lever 15 is suitably pivoted to a microswitch housing 17 and mounts a bearing portion for engaging and inwardly pressing, or releasing, the outwardly biased switch-actuating plunger 18, as is common with micro-switches. Lever 16 is suitably pivoted to a micro-switch housing 20 and mounts a bearing portion for engaging and inwardly pressing, or releasing, the outwardly biased switch-actuating plunger 21, as is also common with micro-switches.

It will be understood that micro-switches are used for convenience and where snap action is essential, and the invention is not limited thereto, as the arms 15 and 16 may comprise contact-carrying members, moving relative to other contacts in switch organizations, as shown in Fig. 8, for example, to be described. Such micro-switches, or other switch organizations, may comprise respectively either single pole, or multi-pole circuit-controlling devices. Movement of lever arm 15, for instance, may be from one made circuit through break, to closing another made circuit, or simply move to make an unmade circuit as a function of lever movement. The same, of course, is true of lever arm 16.

Shaft 12 is subjected to angular mechanical bias, and preferably this is a controllable bias to establish balance with the electromagnetic torsion forces incident on the shaft 12. As shown in Fig. 4, a torsion spring 22 has its inner end connected to the shaft 12, and the outer end is engaged with an adjustable anchor device. Conveniently, this device may comprise an arcuately slotted arm 23 having the anchor extension 24 and an actuating handle 25. The slot 26 is generally concentric with the axis of shaft 12 and engaged by a stud 27, depending from the upper support element 11. The arm 23 is frictionally held where set, but can be manually swung to vary the loading of the torsion spring. The spring 22 is adjusted so that the shaft 12 is biased angularly to such point as to cause roller 14 on arm 13 to engage one of the lever arms 15 or 16, and to close (or open) a circuit controlled by such lever arm.

The shaft 12 mounts a sprocket gear 30, which is in constant mesh with a small pinion gear 31 carried on a jack shaft 32 journaled on the support plate 10 and on an extension support arm 33. Jack shaft 32 mounts a counterbalancing rotor or mass 34, for rotation with but oppositely to shaft 12, as a geared and illustratively, amplified function of rotation thereof. The mass 34 is a smaller mass than the primary mass including the electromagnetic element, to be described, and it is preferred to effect braking thereof through eddy-current effects, by substantially surrounding the mass 34 with radially disposed permanent electromagnets 35, suitably mounted beneath support plate 10.

In order to actuate the relay, the main shaft 12 mounts an electromagnetically-responsive armature. In the preferred embodiment this comprises a generally S-shaped armature 39, having short radial inner arm portions 40 and 41 merging respectively into generally parallel oppositely extending perpendicular intermediate arm portions 42 and 43, which merge respectively into parallel oppositely extending outer arm portions 44 and 45 providing external shoulders 46. The outer arm portions mount the generally arcuate short terminal solenoid core arms 47 and 48, the

curvature of which is concentric generally with the axis of the shaft 12. The armature or rotor thus formed is preferably comprised of laminations, and is symmetrically balanced while having appreciable mass. This is a convenient way to form the armature of plural stampings, although the only essential feature is the oppositely presenting electromagnetically-responsive generally curved terminal members 47 and 48 concentric with the axis of shaft 12. In other words, the arm formation for mounting the terminal members is important but can be changed if desired.

The armature 39, arm 13, roller 14, constitutes a primary mass having a center coincident with the axis of shaft 12. For actuating the armature and thus the shaft 12 against the bias from the torsion spring 22, a pair of spaced hollow electromagnetic coils is provided, as at 50 and 51 respectively, coil 50 has a hollow bore 52 to receive core arm 47 of the armature, and coil 51 has a hollow bore 53 to receive the core arm 48 of the armature. It will be seen that energization of either coil, with a given potential by a solenoid action pulls the juxtaposed arm 47 or 48 into the bore thereof for a proportional distance, against the increasing bias of the torsion spring 22. Owing to the braking, this is a very slow movement, stopping when the electromagnetically-induced torque balances the spring-applied or developed torque. While the coils may be selectively energized in accordance with control circuit operation, it is preferred that they be so coupled into a control circuit as to be equally and simultaneously energized and deenergized. It will be understood that the control circuit for the coils will effect inputs of varying amplitude, thus effecting varying pull on the solenoid arms of the rotor, and that in a sluggish response, the latter will assume a position consonant with balance of opposing mechanical and electrical forces effective on the main shaft 12.

In order to cushion the relay against shock and bouncing back adverse effects, it is preferred to provide a spring-loaded friction stop or dash pot for engagement by the armature rotor in one adjustable position. A simple form thereof is shown in Figs. 2, 4, 7, and 11 hereof. To a suitable post 60 mounted on the support plates or similar devices 10 and 11, a spring housing 61 is mounted, the axis of which is generally tangential of the axis of shaft 12 and mounts the adjustable abutment element 62 in the path of a shoulder or corner 46 of the armature. Preferably the abutment element is disposed to stop the angular motion of the armature under the bias of the torsion spring. While it is sufficient generally to provide but one such abutment, it will be understood that if desired they may be disposed in pairs to limit each end of the armature stroke. The stops are so arranged as to frictionally absorb any kinetic energy of impact.

The essential of the relay is an armature movable in one sense in response to energization of an electromagnetic device, as opposed to a mechanical bias in the other sense. The circuit controllers will be actuated or inert according to the position of arm 13 and roller 14, when balance is achieved. It will be apparent that the result sought can be secured by other forms of mechanism.

Referring to the form of invention shown in Figs. 8 and 9, the main shaft 12 mounts an annular armature 70, of the squirrel cage type, having the embedded copper bars or conductors 75

71. The armature is surrounded by a coil organization 72 of the three phase type. The roller 14 on the arm 13 is disposed between contact arms 15' and 16' for the switch organizations 17' and 20'. These latter are the equivalents of the micro-switches 17 and 20 in the earlier figures, except that they are not of the snap type of the micro-switch. Contact arm 15' is biased to normally "make" contact with contact 13, and to break this contact and to make contact with contact 14 when the roller progressively moves contact arm 15'. Relatedly, contact arm 16' is normally made with contact 15, which is broken, and contact is made with contact 16 under pressure of roller 14 against arm 16'.

As has been noted, the switch organization shown in Fig. 8 can be used interchangeably with the micro-switches of the earlier figures, in either form of the invention.

20 It will be understood that as is preferred in all cases, the squirrel cage rotor 70, arm 13 and roller 14 and stop arm 78 constitute a primary mass having a center coincident with the axis of shaft 12. In an illustrative exemplification of 25 a 1:1 ratio of masses, as shown in Fig. 9, a mass 77, illustratively having the same inertia as that of the primary mass just mentioned, is centered on a jack or stub shaft 32', suitably journaled on the support. A pair of gears, respectively 30' and 79, both having the same diameter and the same number of teeth, are mounted respectively on main shaft 12 and stub shaft 32', so that mass 77 turns oppositely to and has the same inertial effects as the primary mass. Owing to the mass 30 distribution and ratio relative rotations, the primary and secondary masses develop the same inertia and effect mutual counterbalancing in accordance with what has preceded. In effecting 35 braking or damping of the unit, although eddy current brake effects can be resorted to, in accordance with the preceding matter, it may be preferred to utilize other damping. Thus the mass 77 may be submerged in damping fluid such as silicone oil or the like, disposed in a housing 78.

45 In the fragmentary section shown in Fig. 10, the same organization of squirrel cage rotor 70 and main shaft 12 is provided, as in Figs. 8 and 9, but the gearing ratio and the mass ratio is as shown in Figs. 2 and 3, with the smaller mass 34 damped by eddy current effects in the rotation of mass 34 relative to fixed permanent magnets 35.

50 It will be understood that the torque on the primary mass including the squirrel cage rotor varies in accordance with the energization of the three phase windings 72, against the bias from a spring 22, for actuation of the controlled switches in a manner similar to that already described.

55 60 In all cases it will be observed that the relay has a relatively heavy primary rotor movable slowly in angular motion as a resultant of mutually opposing mechanical bias and electromagnetic forces, damped by forces on the counterbalancing mass, and immune to response to both linear and curvilinear accelerations, by reason of the oppositely rotating masses of the same inertia.

Having thus described my invention, I claim:

1. A relay comprising a support, first means having a center of mass, means for supporting said first means at its center of mass for movement relative to said support between limits, second means having a center of mass, means for supporting said second means at its center of mass

for movement relative to said support, linking means connected between the respective first and second means to cause them to move synchronously in opposite relative directions, the ratio of masses and relative rates of synchronous motion of the first and second means effecting substantially equal inertia of the first and second means whereby relative motion of the respective first and second means due to inertia is mutually cancelled to nullify reactions due to accelerative forces incident on said support, means for predeterminedly positioning the first means, and a circuit controller operable as a function of the positioning of said first means.

2. A relay comprising a support, a first mass, means mounting said first mass for oscillation relative to said support between limits on an axis substantially coincident with the center of said mass, a second mass, means mounting said second mass for oscillation relative to said support on an axis substantially coincident with the center of said second mass, means linking the masses for synchronous opposite oscillations, the ratio of angular motions of the masses and the masses being so integrated that both masses have substantially the same inertia and are mutually cancelling in reactions to accelerative forces incident on the support, electromagnetic means for imposing angular torque on one of said masses, and a circuit controller operable as a function of angular position of one of said means.

3. A relay as recited in claim 2, and damping means associated operatively with one of said masses.

4. A relay as recited in claim 2, and eddy-current braking damping means associated with one of said masses.

5. A relay as recited in claim 2, and damping fluid operative on one of said masses.

6. A relay as recited in claim 2, in which the said first and second masses are substantially identical in weight and in which the ratio of synchronous movement thereof is substantially 1:1.

7. A relay as recited in claim 2, in which said first and second masses are unequal in weight and in which the ratio of synchronous movement is other than 1:1.

8. A relay as recited in claim 2, in which one of said masses at least in part constitutes an electromagnetic armature.

9. A relay as recited in claim 2 in which mechanical bias means is provided opposing the torque applied by said electromagnetic means.

10. A relay as recited in claim 2, and a resilient friction stop element forming one of said limits to absorb without rebound impacts of said first mass.

11. A relay comprising a support, a main shaft journalled on the support, an arm mounted on the shaft generally normal thereto, a first and a second circuit-controller mounted on the support in spaced relation on opposite sides of said arm, means on the arm for actuating the respective circuit-controllers with movements of the shaft and arm in the proper appropriate sense, an electromagnetically-responsive rotor mounted on said shaft, coil means mounted on the support for actuating the rotor, and means biasing the shaft and arm toward one circuit-controller actuation.

12. A relay comprising a support, a main shaft journalled on the support, an arm mounted on the shaft generally normal thereto, a first and a

second circuit-controller mounted on the support in spaced relation on opposite sides of said arm, means on the arm for actuating the respective circuit-controllers with movements of the shaft and arm in the proper appropriate sense, complementary electromagnetic means on the shaft and support respectively which when energized moves the shaft and arm toward one circuit-controller, and means biasing the shaft and arm toward the other circuit-controller.

13. A relay as recited in claim 12 in which the complementary electromagnetic means comprises a generally S shaped armature having free-ended oppositely presenting generally arcuate legs, and a spaced pair of hollow coils juxtaposed to said free ends.

14. A relay as recited in claim 12 in which the complementary electromagnetic means comprises a squirrel cage rotor and a three-phase coil winding surrounding said rotor.

15. A relay comprising a support, a main shaft journalled on the support, an arm mounted on the shaft generally normal thereto, a first and a second circuit-controller mounted on the support in spaced relation on opposite sides of said arm, means on the arm for actuating the respective circuit-controllers with movements of the shaft and arm in the proper appropriate sense, complementary electromagnetic means on the shaft and support respectively which when energized moves the shaft and arm toward one circuit-controller, means biasing the shaft and arm toward the other circuit-controller, and stop means limiting the angular motion of the shaft in response to the bias.

16. A relay comprising a support, a main shaft journalled on the support, an arm mounted on the shaft generally normal thereto, a first and a second circuit-controller mounted on the support in spaced relation on opposite sides of said arm, means on the arm for actuating the respective circuit-controllers with movements of the shaft and arm in the proper appropriate sense, complementary electromagnetic means on the shaft and support respectively which when energized moves the shaft and arm toward one circuit-controller, means biasing the shaft and arm toward the other circuit-controller, stop means limiting the angular motion of the shaft in response to the bias, a jack shaft, a rotor mass mounted on the jack shaft, and gearing between the main and jack shafts to actuate the rotor mass as a function of angular motion on said main shaft.

17. A relay comprising a support, a main shaft journalled on the support, an arm mounted on the shaft generally normal thereto, a first and a second circuit-controller mounted on the support in spaced relation on opposite sides of said arm, means on the arm for actuating the respective circuit-controllers with movements of the shaft and arm in the proper appropriate sense, complementary electromagnetic means on the shaft and support respectively which when energized moves the shaft and arm toward one circuit-controller, means biasing the shaft and arm toward the other circuit-controller, stop means limiting the angular motion of the shaft in response to the bias, a jack shaft, a rotor mass mounted on the jack shaft, gearing between the main and jack shafts to actuate the rotor mass as a function of angular motion on said main shaft, and magnetic means juxtaposed to said rotor mass to damp the rotations thereof by eddy current effects.

18. A relay comprising a support, circuit controlling means mounted for pivotal oscillation on

said support, complemental electromagnetic means mounted respectively on said support and on said circuit controlling means, said circuit controlling means and the complemental electromagnetic means mounted thereon having a center of mass substantially coincident with said axis, counterbalancing means pivoted to the support on an axis substantially coincident with the center of mass thereof, driving means connecting said circuit controlling and counterbalancing means for synchronous opposite oscillations, the respective masses of and the driving ratio between the connected means being correlated to

establish similar inertia as functions of mass and respective rotative speeds.

19. A relay as recited in claim 18 and damping means on at least one of the connected means.

20. A relay as recited in claim 18 with shock absorbing means forming at least one limit of oscillation of one of said connected means.
